REVERSIBLE ROTARY PUMP
 Seiji Yamane, 1214 5-chome, Hatanodai, Shinagawa-ku,
 Tokyo-to, Japan
 Filed Sept. 10, 1965, Ser. No. 486,370
 4 Claims. (Cl. 103—143)

This invention relates to a reversible rotary pump having special small rotors mounted on a larger rotor and a casing the inner surface of which is formed by utilizing loci generated on a circle by the rotating small rotors.

An object of the present invention is to provide a rotary pump in which suction and discharge of fluid at the inlets and outlets can be determined depending on the rotating direction of the pump.

Another object of the invention is to provide a rotary pump in which volume of discharge is kept constant without pulsating and generating bubbles.

A further object of the invention is to provide a rotary pump which can operate as a power transmission means by feeding, reversibly, external compressed fluid to the pump.

A further object of the invention is to provide a rotary pump in which suction chambers and discharge chambers can be partitioned or sealed tightly without packings.

A further object of the invention is to provide a rotary pump of very large pumping capacity, high pressure, small size and light weight.

In order to attain these objects, the rotary pump according to the invention comprises a pump casing, a substantially circular relatively large rotor within said casing having a sliding fit therewith at least at a portion of the inner surface of said casing, and at least two small rotors rotably mounted on said large rotor and rotating in an integral ratio thereto. The inner surface of said casing is formed utilizing loci generated by an arbitrary point on the circumference of said small rotors while the contour of said small rotors is such that said small rotors may move in sliding and/or rolling contact with the inner surface of said casing while rotating about their own axes. An inlet and an outlet are provided, respectively at opposite sides of said sliding fit portion of the casing with said large rotor, said inlet and outlet leading to the spaces between said casing and said rotors separated by said sliding fit portion respectively.

Other objects and advantages will be more apparent from the following description and accompanying drawings and in which

FIGS. 1(A) and (B) are diagrams for explaining the principle of one embodiment of the invention,

FIGS. 1(C) and (D) are diagrams for explaining the principle of another embodiment of the invention,

FIG. 2(A) is a cross section view of a rotary pump embodying this invention,

FIG. 2(B) is a fragmentary view along the line M—M' in FIG. 2(A),

FIG. 3 is a longitudinal section view of the pump in FIG. 1,

FIGS. 4(A) to (F) are cross section views similar to that of FIG. 2(A) showing different operating situations,

FIG. 5 is a cross section view showing a gear mechanism of the rotary pump,

FIG. 6 is a cross section view showing a modified construction,

2

FIG. 7 is a cross section view showing other modified construction,

FIG. 8 is a cross section view showing a further modified construction, and

FIG. 9 is a longitudinal section view showing a further modification.

In FIG. 1(A), on the circumference of a circle ϕ_2 , having a radius R_2 and a center at O_2 , is positioned the center point O_1 of a circle ϕ_1 having a radius R_1 which touches internally a circle ϕ_4 concentric with the circle ϕ_2 . Namely, R_4 equals R_1+R_2 . The center point O_1 of the circle ϕ_1 lies on the diameter $Y_1-O_2-Y_2$ of the circle ϕ_2 as shown. Now, suppose that the circle ϕ_2 begins to roll along the inside of the circle ϕ_4 in the direction shown by an arrow u_2 while rotating about its own center in the direction shown by an arrow u_1 , a point P on the periphery of the circle ϕ_1 generates a locus l_1 passing through Y_1 , X , and Y_2 . Similarly a locus l_2 may be obtained by the circle ϕ_1 rolling and rotating in the reverse direction. Here X_1 and X_2 are intersection points of a circle having a radius R_3 and loci l_1 and l_2 . As an example, the relation between rotation of the circle ϕ_1 and movement of its center O_1 along the circle ϕ_2 may be selected to be such that the circle ϕ_1 rotates in the direction u_1 about its center while the center point O_1 rotates about the center O_2 of the circle ϕ_2 in the direction u_2 . When the point O_1 moves around the center O_2 by an angle α to a point O_1' , the point P also moves around the center of the circle ϕ_1 by the angle α to a point P' . P_1 is the intersection point of the locus l_1 and the line passing through O_2 and O_1' . Such intersection points in the range from $\alpha=0$ to $\alpha=90^\circ$ generate a locus l_4 within the circle ϕ_1 as shown in FIG. 1(B). Similarly a locus l_5 is obtained in the range from $\alpha=90^\circ$ to $\alpha=180^\circ$. On the other hand, FIG. 1(B) corresponds to that of the circular arc having the radius R_1 in FIG. 1(A). Finally, if a cam-shaped disc, having an upper curved half l_4-l_5 and a lower circular half with the radius R_1 , moves along the circle ϕ_2 while rotating about the center O_1 , the cam-shaped disc may be kept in sliding contact, at a point, with the inside of an outer circumference having an upper curved half l_1-l_2 and a lower circular half with the radius R_4 .

Next, relation between rotation of the circle ϕ_1 and movement of its center O_1 along the circumference of the circle ϕ_2 may be also selected to be such that the circle ϕ_1 rotates in the direction u_1' about its center as shown in FIG. 1(C), that is, in the opposite direction to that u_1 in FIG. 1(A) while the center point O_1 rotates about the center O_2 along the circle ϕ_2 in the direction u_2 . When the point O_1 moves around the center O_2 by an angle α to a point O_1' , the point P_1 on the circumference of the circle ϕ_1 at the angle α to the line Y_1-O_1 moves around the center of the circle ϕ_1 by the angle α to a point P_1' . Then the point P_1' lies on the line passing through O_2 and O_1' . Further, with movement of the point O_1' to a point O_1'' , the point P_1 moves to a point P_1'' at the same angle α to the line $Y_1''-O_1''$ parallel to the line Y_1-O_2 . Thus a locus l_1' passing P_1', P_1'' and X_1' is obtained by the point P_1 on the circumference of the circle ϕ_1 moving along the circumference of the circle ϕ_2 while rotating about its center. Namely, the point P_1 on the circle ϕ_1 contacts the locus l_1' while keeping always at the constant angle α to the Y_1-Y_2 axis. Similarly the

point ρ_2 symmetrical to the point ρ_1'' generates a locus l_2' passing through X_2' . In FIG. 1(D) the points ρ_1 and ρ_2 thus generate an arc intersecting the circle ϕ_1 . A concave curve l_3 within the circle ϕ_1 is given, in that the points X_1 and X_2 cut the circle ϕ_1 moving along the circle ϕ_2 while rotating about its center.

In FIGS. 2 and 3, 1 designates a pump casing, the inner surface of which corresponds to the outer circumference having the upper curved half l_1-l_2 and the lower circular half with the radius R_4 in FIG. 1(A). The inner surface in the region between X_1 and X_2 is a circular arc having the radius R_3 in FIG. 1(A). Within the casing 1, a large rotor 2 is mounted fixedly on a main shaft 6. A pair of inscribing small rotors 3 and 3', corresponding to a cam-shaped disc having upper curved half l_4-l_5 and the lower circular half with the radius R_1 in FIG. 1(B), are rotably supported by means of shafts 5 and 5' symmetrically with respect to the main shaft 6 on the rotor 2. The space between the casing 1 and the rotor 2 forms enclosed chambers with a front cover 9 and a part of rotor 2 serving as a rear cover.

The surface or side of the large rotor 2 facing the front cover 9 has a radius corresponding to R_3 in FIG. 1(A), while the portion serving as the rear cover thereof is made capable of rotating in sliding contact with the casing 1.

The shafts 5, 5' carrying the small rotors 3, 3' pass through the rear cover portion of the rotor 2 and are secured to planetary gears 13, 11. These planetary gears 13, 11 mesh with a sun gear 12 fixed to a rear plate 10 having a bearing for the main shaft 6. The rear plate 10 is secured to the casing 1 by means of bolts 15. 7 and 8 denote an inlet and an outlet provided in the casing 1 at opposite sides of the sliding fit region X_1-X_2 thereof with the rotor 2. When the main shaft 6 rotates, the rotor 2 also rotates, and the planetary gears 13 and 11, coaxial with the small rotors 3 and 3', revolve around the sun gear 12 while rotating about their axes. Thus the space within the casing 1 is divided by the rear cover portion of the rotor 2 into a gear chamber and a pump chamber in which the small rotors 3, 3' turn with the large rotor 2 while about rotating their own axes in sliding contact with the casing 1. Further, the rotor 2 intercepts the pump chamber in the region X_1-X_2 and divides the casing into two parts, one on each side of said region.

The operation of the pump is shown in FIG. 4. In FIG. 4(A), the upper small rotor 3' is on the midpoint of the inner surface curve of the casing 1, and touches the circular arc portion capable of contacting the rotor 2. The small rotor 3' turns with the rotor 2 while rotating its own axis in the direction as shown. Contact points of the small rotor 3' are always on the inner surface of the casing 1. With rotation the lower small rotor 3 compresses fluids within a compartment E and discharges it through the outlet 7 (see FIGS. 4(A)-(D)). At the same time, suction of new fluid through the inlet 8 is carried out. Either the small rotor 3' or the rotor 2 continues to touch the circular arc portion X_1-X_2 of the inner surface of the casing to divide the pump chamber, and therefore makes easy compression of the fluid in the compartment E by the small rotor 3.

In a position as shown in FIG. 4(E), the compression stroke by the small rotor 3 ends and the compression stroke by the other small rotor 3' begins. Namely, the fluid within a compartment D may flow through an escape slot 4 (see FIG. 2) to the outlet 7. Thus the small rotors 3 and 3' carry out alternately compression and suction in each half rotation of the rotor 2.

Suppose that the pumping stroke is carried out in the region of the lower circular half concentric with the rotor 2 of the casing, the actions of small rotors 3 and 3' maintain a balance between suction and compression, so that discharged volume of the fluid is always constant and not pulsates.

FIGS. 5 and 6 illustrate the embodiment according to the principle shown in FIGS. 1(C) and (D). In FIG. 75

5, the planetary gears 17 are used as intermediate gears interposed between the sun gear 12 and the gears 13 for rotating the small rotors 3, 3'. The intermediate gears 17 are rotably mounted by means of shafts 16 on the rear 10 cover portion of the rotor 2. The small rotors 3, 3' are carried on the shafts 5 of the gears 13 passing through the rear cover portion of the rotor. Here the gear ratio of the sun gear 12 to the gears 13 is selected as 1:1. The rotating direction of the small rotors 3, 3' is opposite to that of the rotor 2. The small rotors 3, 3' have a recess corresponding to the concave curve l_3 as shown in FIG. 1(D). Since the rotating directions of the small rotors 3, 3' and the rotor 2 are opposite to each other, the rotors 3, 3' move in sliding and rolling contact with the inner surface of the casing 1. There is only one intercepting portion partitioning the pumping chamber.

In the embodiment shown in FIG. 7, the gear ratio of the sun gear to the gears for rotating the small rotors is selected as 2:1. In this embodiment, two pumping compartments are formed by two intercepting portions 19 and 19'. The small rotors move in sliding and partly rolling contact with the inner surface of the casing 1.

In FIG. 8, the gear ratio of the sun gear to the gears for rotating the small rotors is selected as 3:1, and the lengths of the circumferences of the small rotors are selected as one third of that of the inner surface of the casing 1, so that the rotors may move in perfectly rolling contact with the inner surface of the casing. Three intercepting portions 20, 21, 22 are formed.

In FIG. 9, the rotor 2 serves not only as a rear cover portion but as a front cover portion in order to prevent the fluid in the pumping chamber from leaking. Small rotors 3 are, therefore, rotably disposed between the front cover portion and the rear cover portion. 24 and 24 denote sliding surface of the rotor 2 and the casing 1. 23 is the inner surface of the casing 1 as described.

What I claim is:

1. A reversible rotary pump comprising, in combination, a casing; a substantially circular relatively large rotor; means rotatably mounting said rotor in said casing, said rotor having at least one peripheral portion engaging at least one arcuate surface portion of the inner surface of said casing; the inner surface of said casing and a peripheral surface of said rotor conjointly defining inlet and outlet chambers extending in opposite angular directions from each arcuate surface portion; at least two relatively small rotors rotatably mounted on said relatively large rotor within said casing; means interconnecting said large rotor and said small rotors for rotation of said small rotors on said large rotor, as the latter rotates about its axis, at an angular velocity which has an integral ratio to the angular velocity of said large rotor; the inner surface of said casing being formed as the loci generated by arbitrary points on the circumferences of said small rotors during rotation of said large rotor; the peripheral contours of said small rotors having a configuration such that said small rotors rotate in continuous contact with the inner surface of said casing during rotation of said large rotor; a fluid inlet port in communication with said inlet chamber; and a fluid outlet port in communication with said outlet chamber.

2. Reversible rotary pump according to claim 1, wherein in said large rotor and said small rotors rotate in the same angular direction.

3. Reversible rotary pump according to claim 1, wherein in said large rotor and said small rotors rotate in opposite angular directions.

4. A reversible rotary pump, according to claim 1, wherein said casing has a circular inner surface axially adjacent said first mentioned inner surface thereof; said relatively large rotor having a pair of axially adjacent portions, one of which has a completely circular periphery in continuous sliding engagement with said second mentioned circular inner surface of said casing, and the other of which has said peripheral portion engaging at

least one arcuate surface portion of the first mentioned inner surface of said casing; said small rotors being mounted in circular recesses in said second mentioned portion of said large rotor, said circular recesses opening outwardly through the periphery of said second mentioned portion of said large rotor.
